UNITED STATES PATENT OFFICE.

WILLIAM F. PAUSE, JR., OF SOUTH CHICAGO, ILLINOIS.

MOLD FOR MAKING CEMENT RECEPTACLES.

1,178,409.

Specification of Letters Patent.

Patented Apr. 4, 1916.

Application filed September 4, 1915. Serial No. 49,056.

To all whom it may concern:

Be it known that I, WILLIAM F. PAUSE, Jr., a citizen of the United States, residing at South Chicago, in the county of Cook and State of Illinois, have invented new and useful Improvements in Molds for Making Cement Receptacles, of which the following is a specification.

This invention relates to improvements 10 in molds and, in the present instance, is directed more particularly to a mold for making cement refuse receptacles.

In carrying out the present invention, it 15 is my purpose to provide a mold of the class described whereby garbage receptacles may be molded from cementitious substances and wherein the component parts of the mold may be readily knocked down after the substance has set, thereby enabling the mold 20 to be removed from the receptacle, and wherein such parts may be rapidly assembled in mold formation when it is desired to form the receptacle.

It is also my purpose to provide a mold of 25 the class described which will embrace the desired features of simplicity, efficiency and durability, which may be manufactured and marketed at minimum expense and which may be conveniently handled.

With the above and other objects in view, 30 the invention consists in the construction, combination and arrangement of parts hereinafter set forth in and falling within the scope of the claims.

In the accompanying drawings; Figure 1 35 is a view in end elevation of a mold constructed in accordance with the present invention. Fig. 2 is a vertical sectional view through the mold. Fig. 3 is a similar view 40 taken at right angles to Fig. 2. Fig. 4 is a horizontal sectional view through the mold. Fig. 5 is a perspective view of the receptacle formed by the mold.

Referring now to the drawings in detail, 45 1 designates an outer form substantially rectangular in cross section and having the top and bottom ends thereof open and the front end wall formed with a substantially rectangular opening 2. In the present instance, 50 this outer form comprises sections 3, 3 of right angular formation and having the corresponding edges thereof connected together by means of latches 4.

Mounted within the outer form 1 is an 55 inner form 5 having one end open as at 6 and the remaining end closed. The open end of the inner form 5 is disposed within the opening

2 in the outer form and the vertical edges of the side walls of the inner form and the open end thereof are flanged outwardly as 60 at 7 to engage the outer surface of the adjacent end wall of the outer form. The end wall and the side walls of the inner form 5 are spaced apart from the end and side walls respectively of the outer form so as 65 to provide a space for the cementitious substance to be molded. The bottom wall of the inner form 5 is spaced apart from the lower edges of the side and end walls of the outer form and the rear portion of the 70 bottom wall of the inner form is disposed in a horizontal plane, while the forward portion is inclined upwardly as at 8 from the rear portion and has the forward edge thereof lying flush with the lower edge wall 75 of the opening 2 in the outer form. In the present instance, this inner form 5 comprises a lower section 9 and an upper section 10 placed upon the lower section. The confronting edges of the upper and lower 80 sections are inturned as at 11 and formed with alining bolt holes and passed through these alining bolt holes are bolts 12 whereby the sections may be secured together. Each section 9, 10 of the form embodies 85 two sub-sections 13 of right angular formation and having the confronting edges thereof flanged inwardly as at 14 and formed with alining bolt holes 15 designed to receive securing bolts 16 whereby the sub- 90 sections may be secured in section formation. Closing the upper end of the inner form 5 and resting upon the top edges of the end wall and the side walls of such form is a plate 17 formed with a substantially rectangular opening 18 adjacent to the forward edge thereof. 95

19 designates a substantially rectangular frame disposed within the opening 18 and having the upper edge portion offset outwardly from the lower edge portion, the shoulder formed at the juncture of the offset portion with the remaining portion seating upon the upper surface of the plate 17 adjacent to the marginal edges of the opening 18 to support the frame within the opening.

In practice, the inner form is assembled and the sections of the outer form put together and the inner form disposed within 110 the outer form as illustrated in the drawings, the plate 17 closing the upper end of the inner form, while the upper portion of the frame 19 projects above the plate 17

around the opening 18. The front edges of the side and bottom walls of the inner form are secured to the corresponding edges of the opening in the outer form so that the 5 inner form may be properly held within the outer form. The cementitious material is now poured into the spaces between the side and end walls of the inner and outer forms and flows below the bottom wall of the 10 inner form and when the spaces between the side and end walls of the forms are filled, the plate 17 is covered with the material to be molded, the frame 19 preventing such material from falling through the 15 opening 18. As the cement or other material flows beneath the bottom wall of the inner form, such material takes the shape of the bottom wall and after the material has hardened, the sections and sub-sections 20 of the inner form are assembled and removed through the opening in the front end wall of the outer form, the plate 17 removed, and the sections of the outer form detached and removed. The receptacle thus formed 25 has an opening in one end wall and the bottom wall of the receptacle inclines downwardly from the opening in the end wall toward the opposite end wall, as clearly illustrated in Fig. 5 of the drawings. This 30 receptacle is adapted to receive garbage and when in use is placed upon the ground with the open end wall disposed within an opening in the fence of the yard and flush with such fence. The open end wall of the receptacle 35 is preferably closed by means of a suitable door, while the opening in the top wall is closed by means of a removable cover and when it is desired to throw the refuse into the receptacle the cover on the top wall 40 thereof is removed and the garbage thrown into the receptacle. To remove the refuse from the receptacle, the door closing the outer end wall thereof is swung to open position and the refuse removed by means of a 45 shovel or the like, the inclined bottom wall of the receptacle facilitating the use of the shovel.

I claim:

1. A mold of the class described comprising an outer form substantially rectangular in cross section and having one end wall thereof formed with an opening, an inner form disposed within said outer form and having one end disposed within the opening in the end wall of said outer form and the remaining end wall and the side walls spaced apart from the end and side walls respectively by said outer form, the end of said inner form within the opening in the 55 outer form being open, the bottom wall of said outer form being open, the bottom wall of said inner form having the end portion remote 60 from the open end disposed in a horizontal plane and the remaining end portion inclined upwardly and abutting the bottom wall of the opening in said outer form, a plate closing the upper end of said inner form and having an opening formed therein, a frame within said opening and projecting above the plate substantially as, and for the purpose, described, said outer form comprising a number of sections, and means holding said sections and sub-sections together.

note from the open end disposed in a horizontal plane and the remaining end portion inclined upwardly and abutting the bottom wall of the opening in said outer form, a plate closing the upper end of said inner form and having an opening formed therein, and a frame within said opening and projecting above the plate substantially as, and for the purpose, described. 65

2. A mold of the class described comprising an outer form substantially rectangular in cross section and having one end wall thereof formed with an opening, an inner form disposed within said outer form and having one end disposed within the opening in the end wall of said outer form and the remaining end wall and the side walls spaced apart from the end and side walls respectively by said outer form, the end of said inner form within the opening in the outer form being open, the bottom wall of said inner form having the end portion remote from the open end disposed in a horizontal plane and the remaining end portion inclined upwardly and abutting the bottom wall of the opening in said outer form, a plate closing the upper end of said inner form and having an opening formed therein, a frame within said opening and projecting above the plate substantially as, and for the purpose, described, said outer form comprising a number of sections, and means for detachably securing said sections together. 70

3. A mold of the class described comprising an outer form substantially rectangular in cross section and having one end wall thereof formed with an opening, an inner form disposed within said outer form and having one end disposed within the opening in the end wall of said outer form and the remaining end wall and the side walls spaced apart from the end and side walls respectively by said outer form, the end of said inner form within the opening in the outer form being open, the bottom wall of said inner form having the end portion remote from the open end disposed in a horizontal plane and the remaining end portion inclined upwardly and abutting the bottom wall of the opening in said outer form, a plate closing the upper end of said inner form and having an opening formed therein, a frame within said opening and projecting above the plate substantially as, and for the purpose, described, said inner form comprising a number of sections and sub-sections, and means holding said sections and sub-sections together. 75

In testimony whereof I affix my signature.
WILLIAM F. PAUSE, JR.
